RATCHET-TYPE WRENCH

David E. Haenni, 310 4th Ave., and John W. Haenni,
406 Ave. G, both of Sterling, Ill.
Filed Jan. 11, 1961, Ser. No. 81,968
7 Claims. (Cl. 81—126)

This invention relates to improvements in ratchet-type wrenches.

An important object of this invention is to provide a ratchet-type wrench which is of simple and economical construction and which is reliable in operation.

A more particular object of this invention is to provide a ratchet-type wrench including a fixed jaw and a movable jaw, and having an improved arrangement for mounting the movable jaw movement toward and away from the fixed jaw and which automatically locks the movable jaw against movement when the wrench is turned in one direction and releases the movable jaw to enable the latter to move away from the fixed jaw, when the wrench is turned in the opposite direction.

Another object of this invention is to provide a ratchet wrench in accordance with the foregoing objects and which is adjustable to accommodate different sized workpieces.

An important feature of this invention resides in the use of an over-center linkage for mounting a movable jaw member for movement relative to a fixed jaw member, and which linkage is operable to automatically lock the movable member against movement when the wrench is turned in one direction, and to release the movable jaw and enable movement of the same away from the fixed jaw when the wrench is moved in the opposite direction.

These, together with various ancillary objects and advantages of this invention will be more readily appreciated as the same becomes better understood by reference to the following detailed description when taken in connection with the accompanying drawings wherein:

FIGURE 1 is a side elevational view of a ratchet wrench embodying the present invention, and with part of the side cover plate broken away to illustrate the details of construction;

FIGURE 2 is a longitudinal sectional view through the wrench taken on the plane 2—2 of FIG. 1;

FIGURE 3 is a fragmentary side elevational view of the wrench, illustrating the position of the movable jaw member during ratcheting of the wrench; and

FIGURE 4 is a side elevational view of the modified form of wrench.

The wrench includes a body 10 and, in the form shown, the body includes an elongated central bar 11, and spaced side plates 12 and 13 which are secured to the opposite sides of the central bar as by fasteners 14. As shown in FIGURE 1, fasteners 14 are in the form of countersunk flat-headed screws. The wrench of the embodiment of FIGURES 1-3 is of the double ended type having fixed and movable jaw members at each end of the body. The jaw members are similarly constructed and are dimensioned for use on relatively different size workpieces, such as nuts or bolts 16. For convenience, the same numerals are used to designate corresponding parts at each end of the wrench and the parts at one end of the wrench are differentiated from the other end by the use of the designation “”. More particularly, the wrench includes fixed jaw members 17 and 17' defining jaw faces 18 and 18' respectively. As shown in FIGURES 1 and 3, the jaw members are of the box-end type which encircle the heads of the workpieces 16, it being apparent that the jaw members could be opened at one side or the other of the respective jaw faces 18 and 18'. Movable jaws 19 and 19' are mounted on opposite ends of the wrench body for limited movement toward and away from the respective

2

fixed jaw faces 18 and 18'. For this purpose, recesses or cavities 21 and 21' are formed in opposite ends of the central bar 11, with the outer ends of the recesses opening into the workpiece receiving openings formed by the respective jaw members 17 and 17'. The cavities 21 and 21' are each dimensioned at the outer ends 22 thereof to guidably engage the outer end of the respective movable jaw member therebetween and to support the outer end of the jaw member for movement toward and away from the fixed jaw member. The inner ends of the cavities 21 and 21' are relatively wider than the inner ends of the respective jaw members to permit the inner ends of the jaw members to swing crosswise of the wrench body. As will be noted from FIGURE 2, the side plates 12 and 13 engage opposite faces of the movable jaw members to guide the inner ends thereof during movement crosswise of the wrench body.

The inner ends of the movable jaw members 19 and 19' are swingably mounted on the body by means of an over-center type linkage 25 and 25', respectively. The linkages each include a pair of spaced links which are pivotally attached at one end by means of a pin 26 to an ear 27 on the inner end of the respective movable jaw member. The end of each link is pivotally attached by a pin 28 to an ear 29 carried by the wrench body. The linkage swingably supports the inner ends of the jaw members for movement between a position such as shown in FIGURE 1 and the position shown at FIGURE 3, and a stop is provided for limiting swinging movement of the movable jaw members in one direction to a position in which a line through the pivot pins 28 and 26 intersects the jaw face 31 on the respective movable jaw member. In the form shown, one side 32 of each of the cavities 21 and 21' are shaped to engage the respective movable jaw member and limit swinging movement of the same in one direction to the aforescribed position, as shown in FIGURE 1. The jaw faces 31 on the movable jaw members are shaped so as to extend substantially parallel to the respective fixed jaw face 18 and 18', when the movable jaw member is against its stop, so that the fixed and movable jaw members firmly clamp opposite sides of the workpiece 16 therebetween. A spring 33 is provided for yieldably urging the jaw member toward its stop and, as shown, the spring is of the leaf type and has an eyelet at one end which is supported in a socket 34 formed at one side of the cavity 21 in the end of the wrench. The spring engages the movable jaw member adjacent to its inner end to yieldably urge the same against the stop face 32.

When the wrench is turned in one direction, for example in a clockwise direction, about its upper end as viewed in FIGURE 1, the workpiece 16 applies pressure to the movable jaw face 31 at a point designated *a* which is offset to one side of the line through the pivot pins 26 and 28 and therefore presses the jaw member firmly against the stop 32 so that the latter is locked against movement away from the fixed jaw face 18. However, when the wrench is turned in the opposite direction, that is in a counter-clockwise direction about its upper end as viewed in FIGURE 1, the workpiece applies pressure to the jaw face 31 at a point such as *b* which is offset to the other side of the line through the pivot pins 26 and 28 and which therefore presses the jaw member away from the stop 32 to a collapsed position such as shown in FIGURE 3. This allows the wrench to ratchet relative to the workpiece 16.

In the embodiment shown in FIGURES 1-3, provision is made for adjusting the movable jaw members in a direction toward and away from the respective fixed jaw members to accommodate different size workpieces. A common adjusting mechanism is provided for adjusting the jaw members at opposite ends of the double-ended

wrench, and for this purpose a rod 38 is slidably mounted in a groove 39 extending between the cavities 21 and 21'. The ear 29 which is connected to one of the jaw members 19 is formed at one end of the rod 38 and the ear 29' which is attached to the other jaw member 19' is formed on the other end of the rod. The rod is threaded as indicated at 41 along a portion of its length and a knurled nut 42 is threaded on the rod. The bar 11 is formed with recesses 43 and 44 intermediate its ends, which recesses intersect the groove 39 and define shoulders 45 and 46 engageable with opposite ends of the nut 42 to prevent axial movement of the same. As shown in FIGURE 2, the nut 42 projects through openings 48 in the opposed side plates 12 and 13 to enable manipulation of the nut. Turning of the nut shifts the rod 38 longitudinally in a direction toward and away from the fixed jaw faces 18 and 18' and correspondingly shifts the movable jaw members to accommodate different size workpieces. Necessarily, the sides of the rigid jaw members 17 and 17' which extend between the jaw faces 18 and 18' and the cavities, respectively 21 and 21', are made sufficiently large to accommodate the largest size workpiece that can be handled by that end of the wrench, and to enable turning of the workpiece therein, as the wrench ratchets relatively to the workpiece.

The wrench shown in FIGURE 4 is similar to the embodiment of FIGURES 1-3 and includes an elongated body 51 having a recess 52 extending inwardly of one end thereof and sideplates 53 overlying opposite sides of the recess to define a cavity for receiving the movable jaw member 54. A fixed jaw member 55 is formed on the end of the wrench and defines a fixed jaw face 56 which is spaced from the outer end of the recess 52, and away from the face 57 of the movable jaw member. The outer end of the recess 52 is dimensioned to guidably support the outer end of the movable jaw member 54, and the inner end of the jaw member is swingably mounted by means of links 58 on the body 51. As shown, the links 58 are connected by a pin 59 to an ear 61 on the inner end of the movable jaw member, and by a pin 62 to an ear 63 on the body. The side 64 of the cavity defines a stop which engages the movable jaw member to limit movement thereof in one direction to a position in which a line through the pivot pins 59 and 62 intersects the jaw face 57. A leaf spring 68 has one end 69 thereof mounted on the body and the other end arranged to engage the inner end of the movable jaw member to yieldably urge the same against the stop 64.

As is apparent from FIGURE 4, the fixed jaw face 56 is disposed at a substantial angle to the longitudinal axis of the body 51 and the fixed jaw member is open at one side of the jaw face 56. The jaw face 57 on the movable jaw member is shaped to extend substantially parallel to the fixed jaw face, when the movable jaw member engages the stop 64, so as to engage opposite sides of the workpiece 16 therebetween. When the wrench is turned in a clockwise position as viewed in FIGURE 4, pressure is applied to the movable jaw face 57 at one side of the line through the pivot pins 59 and 62, so as to lock the movable jaw member against the stop and thereby enable turning of the piece 16. When the wrench is moved in the other direction counterclockwise as viewed in FIGURE 4, pressure is applied to the movable jaw at the other side of the line through the pivot pins 59 and 62 so that the movable jaw is pressed away from the stop 64 and the jaw swings about the link 58 to the dotted line position shown in FIGURE 4. As the jaw member swings to the dotted line position, it is retracted inwardly in a direction away from the fixed jaw face 56 so as to enable the wrench to turn relative to the workpiece.

From the foregoing it is thought that the operation and construction of the wrenches will be readily understood. When the wrench is turned in one direction relative to the workpiece, pressure is applied to the movable jaw

member at one side of the line through the pivot axes of the link, so that the jaw member is moved against the stop to firmly lock the jaw member against retraction. Turning of the wrench in this direction will therefore effect turning of the workpiece 16 therewith. If it is desired to turn the workpiece in the other direction, it is only necessary to turn the wrench over and insert the workpiece 16 between the fixed and movable jaws from the opposite side of the wrench. When the wrench is turned in a relatively opposite direction, pressure is applied to the movable jaw at the other side of the line through the pivot axes of the over-center linkage so as to move the jaw member away from the stop. As the inner end of the jaw member swings about the over-center linkage, it is retracted inwardly of the cavity and away from the fixed jaw face so as to enable the workpiece to turn between the fixed and movable jaw faces. In the embodiment of FIGURES 1-3, the movable jaw members are adjustable to a limited extent in a direction toward and away from the fixed jaw faces so as to accommodate different size workpieces. As will be noted, the double-ended construction of FIGURE 1 is so arranged that a single adjusting mechanism operates to adjust both movable jaw members.

25 We claim:

1. A ratchet-type wrench comprising an elongated body having a cavity opening at one end thereof, means defining a first jaw spaced from the end of said cavity, a movable jaw member disposed in said cavity and having a second jaw face on the outer end thereof, a link pivotally attached at one end to the inner end of said jaw member, means pivotally attaching the other end of the link to said body to swingably support the inner end of said jaw member on the body, said cavity being shaped to guidably engage the outer end of the jaw member whereby the second jaw face on the jaw member moves toward and away from the first jaw face as the inner end of the jaw member pivots on said link relative to said body, stop means on the body engageable with the jaw member for limiting swinging movement in one direction, and means yieldably urging the jaw member toward said stop means.

2. The combination of claim 1 wherein said body includes a central portion and plates overlying opposite sides of said central portion to define said cavity.

3. A ratchet type wrench comprising, an elongated body having a handle portion and a first jaw face adjacent one end of said handle portion, an elongated movable jaw member having a second jaw face adjacent one end and a length which is long as compared to the width of said second jaw face, means mounting said movable jaw member on said body for movement in response to the pressures applied by a workpiece engaging said second jaw face between a first position in which said second jaw face extends generally parallel to said first jaw face and is spaced a preselected distance therefrom to grip the workpiece therebetween when the wrench is turned in one direction and a second position in which said second jaw face is tilted out of parallelism with said first jaw face and is spaced therefrom a distance greater than said preselected distance to allow the workpiece to turn relative to the jaw faces when the wrench is turned in the opposite direction, said last mentioned means including a first guide means on said body slidably supporting said one end of the movable jaw member on said body for movement in a direction generally lengthwise of the jaw member toward and away from said first jaw face and also pivotally supporting said one end of said movable jaw member on said body to permit limited lateral swinging movement of the other end of said movable jaw member as the jaw member moves between said first and second positions, stop means on said body engageable with said movable jaw member when the latter reaches said first position for limiting lateral swinging movement of said other end of said movable jaw member in one direction, means yield-

ably urging said movable jaw member toward said first position and against said stop means, said mounting means also including a second guide means engaging said other end of said movable jaw member for controlling endwise movement of said movable jaw member and operative to position said second jaw face said preselected distance from said first jaw face when said movable jaw member is in said first position against said stop means and for retracting said movable jaw member away from said first jaw face as said other end of said movable jaw member swings laterally away from said stop means to said second position.

4. A ratchet type wrench comprising, an elongated body having a handle portion and a first jaw face adjacent one end of said handle portion, an elongated movable jaw member having a second jaw face adjacent one end and a length which is long as compared to the width of said second jaw face, means mounting said movable jaw member on said body for movement in response to the pressures applied by a workpiece engaging said second jaw face between a first position in which said second jaw face extends generally parallel to said first jaw face and is spaced a preselected distance therefrom to grip the workpiece therebetween when the wrench is turned in one direction and a second position in which said second jaw face is tilted out of parallelism with said first jaw face and is spaced therefrom a distance greater than said preselected distance to allow the workpiece to turn relative to the jaw faces when the wrench is turned in the opposite direction, said last mentioned means including a first guide means on said body slidably supporting said one end of the movable jaw member on said body for movement in a direction generally lengthwise of the jaw member toward and away from said first jaw face and also pivotally supporting said one end of said movable jaw member on said body to permit limited lateral swinging movement of the other end of said movable jaw member as the jaw member moves between said first and second positions, stop means on said body engageable with said movable jaw member when the latter reaches said first position for limiting lateral swinging movement of said other end of said movable jaw member in one direction, means yieldably urging said movable jaw member toward said first position and against said stop means, said mounting means also including a link pivotally attached at one end to said other end of said movable jaw member, said link being short as compared to the distance between said second jaw face and the point of attachment of the link to the movable jaw member, means pivotally attaching said other end of the link to said body for controlling endwise movement of said movable jaw member and operative to position said second jaw face at said preselected distance from said first jaw face when said movable jaw member is in said first position against said stop means and for retracting said movable jaw member away from said first jaw face as said other end of the movable jaw member swings laterally away from said stop means to said second position.

5. A ratchet type wrench comprising, an elongated body having a handle portion and a first jaw adjacent one end of said handle portion, an elongated movable jaw member having a second jaw face adjacent one end and a length which is long as compared to the width of said second jaw face, means mounting said movable jaw member on said body for movement in response to the pressures applied by a workpiece engaging said second jaw face between a first position in which said second jaw face extends generally parallel to said first jaw face and is spaced a preselected distance therefrom to grip the workpiece therebetween when the wrench is turned in one direction and a second position in which said second jaw face is tilted out of parallelism with said first jaw face and is spaced therefrom a distance greater than said preselected distance to allow the workpiece to turn relative to the jaw faces when the wrench is turned in the opposite direction, said last mentioned means including first and second guide walls on said cavity slidably supporting said outer end of said movable jaw member on said body for movement in a direction generally lengthwise of the jaw member toward and away from said first jaw face and also pivotally supporting said outer end of said movable jaw member to permit limited lateral swinging movement of the inner end of said movable jaw member as said jaw member moves between said first and second positions, said first guide wall defining a stop face engageable with said movable jaw member when the latter reaches said first position for limiting lateral swinging movement of said inner end of said movable jaw member in one direction, said second guide wall being spaced from said inner end of said movable jaw member when the latter is in said first position, means yieldably urging said movable jaw member toward said first position and against said stop means, said mounting means also including a link pivotally attached at one end to the inner end

site direction, said last mentioned means including a first guide means on said body slidably supporting said one end of the movable jaw member on said body for movement in a direction generally lengthwise of the jaw member toward and away from said first jaw face and also pivotally supporting said one end of said movable jaw member on said body to permit limited lateral swinging movement of the other end of said movable jaw member as the jaw member moves between said first and second positions, stop means on said body engageable with said movable jaw member when the latter reaches said first position for limiting lateral swinging movement of said other end of said movable jaw member in one direction, means yieldably urging said movable jaw member toward said first position and against said stop means, said mounting means also including a link pivotally attached at one end to said other end of said movable jaw member, said link being short as compared to the distance between said second jaw face and the point of attachment of the link to the movable jaw member, means pivotally attaching said other end of the link to said body for controlling endwise movement of said movable jaw member and operative to position said second jaw face at said preselected distance from said first jaw face when said movable jaw member is in said first position against said stop means and for retracting said movable jaw member away from said first jaw face as said other end of the movable jaw member swings laterally away from said stop means to said second position, the pivot connections of the link to the movable jaw member and to the body being located such that a line through the pivot connections intersects the second jaw face when said movable jaw member engages said stop means.

6. The combination of claim 5 wherein said means pivotally attaching said link to said body includes means for adjusting the pivot connection of the link to the body in a direction toward and away from said first jaw face to accommodate different work pieces.

7. A ratchet type wrench comprising an elongated body having a cavity opening at one end thereof, means defining a first jaw face spaced from the end of the cavity, an elongated movable jaw member disposed in said cavity and having a second jaw face on the outer end thereof and a length which is long as compared to the width of said second jaw face, means mounting said movable jaw member on said body for movement in response to pressures applied by a workpiece engaging said second jaw face between a first position in which said second jaw face extends generally parallel to said first jaw face and is spaced a preselected distance therefrom to grip a workpiece therebetween when the wrench is turned in one direction and a second position in which said second jaw face is tilted out of parallelism with said first jaw face and is spaced therefrom a distance greater than said preselected distance to allow the workpiece to turn relative to the jaw faces when the wrench is turned in the opposite direction, said last mentioned means including first and second guide walls on said cavity slidably supporting said outer end of said movable jaw member on said body for movement in a direction generally lengthwise of the jaw member toward and away from said first jaw face and also pivotally supporting said outer end of said movable jaw member to permit limited lateral swinging movement of the inner end of said movable jaw member as said jaw member moves between said first and second positions, said first guide wall defining a stop face engageable with said movable jaw member when the latter reaches said first position for limiting lateral swinging movement of said inner end of said movable jaw member in one direction, said second guide wall being spaced from said inner end of said movable jaw member when the latter is in said first position, means yieldably urging said movable jaw member toward said first position and against said stop means, said mounting means also including a link pivotally attached at one end to the inner end

of said jaw member, means pivotally attaching the other end of said link to said body for controlling endwise movement of said movable jaw member, the pivot connections of said link to said movable jaw member and to the body being located such that line through the pivot connections intersects the second jaw face when said movable jaw member engages said stop means.
